(57) **CLAIM**

The ornamental design for an electric hairdressing device, as shown and described.

DESCRIPTION

FIG. 1 is a perspective view of an electric hairdressing device in accordance with the present invention.

FIG. 2 is a right side view thereof.

FIG. 3 is a left side view thereof.

FIG. 4 is a front view thereof.

FIG. 5 is a back view thereof.

FIG. 6 is a top view thereof.

FIG. 7 is a bottom view thereof; and,

FIG. 8 is a perspective view in a closed configuration thereof.

The broken lines are included for the purpose of illustrating portions of the electric hairdressing device that form no part of the claimed design.
